UNITED STATES PATENT OFFICE.

JESSE H. SROFE, OF KOKOMO, INDIANA.

DESIGN FOR A WIRE FENCE.

SPECIFICATION forming part of Design No. 31,475, dated August 29, 1899.

Application filed August 7, 1899. Serial No. 726,479. Term of patent 7 years.

To all whom it may concern:

Be it known that I, JESSE H. SROFE, a citizen of the United States, residing at Kokomo, in the county of Howard and State of Indiana, have invented and produced a certain new Design for a Wire Fence, of which the following is a specification.

In the drawings, Figure 1 is an elevation of a wire fence presenting my design, and Fig. 2 a detail view of one of the pickets.

As shown in the drawings, the leading or important feature of my design consists in a fence having horizontal strand-wires A, B, C, D, and E, running longitudinally through the fence, and the double pickets F, having curved tops which cross each other, as shown, above the top horizontal strand A, and which have inclined portions f, converging toward each other through the space between the horizontal strands A and B, meeting at the strand B and then diverging from each other

in opposite curves and converging again to form ovals f' between the strands B and C, and the inclined portions f², diverging from each other between the horizontal strands C and D, and the inclined portions f³, converging toward each other through the space between the strands D and E, and the inclined portions f⁴ below the strand E, forming the diverging ends, as shown.

What I regard as new, and wish to secure by Letters Patent, is—

The design for a wire fence herein shown and described.

In witness whereof I have hereunto set my hand and seal, at Indianapolis, Indiana, this 24th day of July, A. D. 1899.

JESSE H. SROFE. [L. S.]
